UNITED STATES PATENT OFFICE.

PETER F. HABERSTICK, OF WHEELING, WEST VIRGINIA.

INITIATION APPARATUS.

SPECIFICATION forming part of Letters Patent No. 766,614, dated August 2, 1904.

Application filed April 14, 1904. Serial No. 203,162. (No model.)

To all whom it may concern:

Be it known that I, PETER F. HABERSTICK, a citizen of the United States of America, and a resident of Wheeling, county of Ohio, and 5 State of West Virginia, have invented certain new and useful Improvements in Initiation Apparatus, of which the following is a specification.

My invention relates to initiation devices, 10 and more particularly to a device especially adapted for initiation purposes; and it consists in the particular construction, arrangement, and combination of parts which will hereinafter be fully described.

15 The primary object of the invention is to provide an illusion apparatus for initiation purposes, the same being adapted for creating in the imagination of a blindfolded person placed thereon a delusion to the effect that he 20 is suspended in the air upon an unstable platform and is being gradually elevated to a great height.

25 A still further object of the invention is to provide an apparatus for producing a sensation of dizziness in a blindfolded person placed thereon which is somewhat akin to that produced by the continued rocking of a boat.

In describing my invention in detail reference is herein had to the accompanying drawings, forming a part of this specification, in 30 which—

Figure 1 is a perspective view of the invention complete. Fig. 2 is a side elevation of the same, partly in section. Fig. 3 is a rear 35 end elevation of the truck, and Fig. 4 is an enlarged vertical section illustrating the supporting means for the elevated platform.

Referring to said drawings, in which like reference-numerals designate like parts throughout the several views, 1 indicates a roadway or track upon which is mounted a movable truck 2. Said truck consists of a low platform 3, mounted upon bolsters 4, which rest upon axles 5. Flanged wheels 6 on the ends 45 of said axles support the body of said truck and travel upon said track 1.

On said platform 3, at each of the four corners thereof, is mounted a post 7, which posts serve as supports for light spiral springs 8, 50 which stand in vertical positions with their

bases encircling said posts. A platform 9 is mounted upon said springs 8 in any suitable manner, but preferably as shown in the drawings, in which fixed downwardly-extending posts 10 are held within the upper ends of 55 said spiral springs. The posts 7 and the posts 10 are each short as compared with the length of the springs 8, so that quite a space is left between the free ends of the posts. The springs being comparatively light and weak, 60 the platform 9 has a decided tendency to sway and rock back and forth from one side to another, and especially so when subjected to the weight of a person thereon.

At the front end of the track or roadway 1 65 is provided a windlass, consisting of upright posts or supports 11, in the upper ends of which is journaled a crank-shaft 12 with a crank 13 upon one of its outer ends. A rod 14 is preferably supported by said posts 11, 70 near the base thereof, and a pulley-wheel 15 is mounted on said rod. A rope 16, attached to the front end of the truck 2, is passed about said pulley-wheel 15 and runs thence to the crank-shaft 12. By manipulating the windlass 75 the truck 2 is easily drawn along the track toward said windlass.

In operation the subject for initiation is blindfolded and placed upon the platform 9, which with every movement made by him 80 sways and rocks in a manner which to him is seemingly calculated to upset. Then using the windlass the truck is slowly drawn forward, producing in the subject the belief that he is being slowly drawn high in the air upon 85 an unstable footing, with all the sensations usually accompanying such a performance. A ratchet 17, secured upon one end of the crank-shaft 12, with a spring 18 in engagement therewith, serves the double purpose of holding 90 the truck against retraction on the track and of a noise-maker which assists in adding confusion to the subject and in carrying out the deception.

It will be seen from the foregoing that I 95 have described my invention in a simple form; but it is obvious that various slight changes may be made in the construction and in the arrangement of parts without departing from the general spirit or scope of the invention. 100

Hence I do not desire to limit myself to the precise construction herein shown and described.

Having thus described my invention, what I claim as new, and desire to secure by Letters Patent, is—

1. In an initiation apparatus, a truck, spiral springs, swayable laterally in all directions, mounted on said truck, and a platform mounted upon said springs to sway and rock therewith, substantially as described.

2. In an initiation apparatus, a truck, spiral springs, laterally swayable in all directions, mounted upon said truck, said springs adapted to sway unimpeded, a platform mounted upon said springs to sway and rock thereon, a windlass, and a rope connecting said windlass with said truck, substantially as described.

3. In an initiation apparatus, a truck, a stationary platform on said truck, short posts on each of the four corners of said platform, spiral springs, swayable laterally and unimpededly in all directions, mounted upon said posts, and a second platform mounted upon

said springs and swayable therewith, substantially as described.

4. In an initiation apparatus, a track, a truck movable upon said track, springs carried by said truck, a platform mounted on said springs to sway and rock therewith, a windlass at one end of said track, a rope connecting the windlass with the truck, and a pawl and ratchet on said windlass, substantially as described.

5. In an initiation apparatus, the combination with a track, a truck, and means for drawing said truck forward on said track, of laterally-swayable spiral springs mounted in upright positions on said truck, said springs adapted to sway unimpeded in all directions, and a platform mounted on said springs and swayable therewith, substantially as described.

Signed by me in the presence of two subscribing witnesses.

PETER F. HABERSTICK.
